(57) **CLAIM**

The ornamental design for tobacco pouches, as shown and described.

DESCRIPTION

FIG. 1 is a top view of an arrangement of a first embodiment of the disclosed tobacco pouches;

FIG. 2 is a top perspective view thereof;

FIG. 3 is a top view of an arrangement of a second embodiment thereof;

FIG. 4 is a top perspective view thereof;

FIG. 5 is a top view of an arrangement of a third embodiment of the disclosed tobacco pouches, including surface texture;

FIG. 6 is a top perspective view thereof;

FIG. 7 is a top view of an arrangement of a fourth embodiment thereof; and,

FIG. 8 is a top perspective view thereof.

The broken lines shown in FIGS. 1-8 depict environmental subject matter and form no part of the claimed design.

1 Claim, 4 Drawing Sheets
